UNITED STATES PATENT OFFICE.

JOHN THOMAS FANNING, OF MOONEE PONDS, VICTORIA, AUSTRALIA.

MEANS FOR REENFORCING TOILET AND OTHER COMBS.

Application filed April 29, 1924. Serial No. 709,767.

To all whom it may concern:

Be it known that I, JOHN THOMAS FANNING, subject of the King of Great Britain, residing at 7 Thomas Street, Moonee Ponds, 5 in the State of Victoria, Australia, have invented certain new and useful Improvements in Means for Reenforcing Toilet and Other Combs; and I do declare the following to be a full, clear, and exact description of the 10 invention such as will enable others skilled in the art to which it appertains to make and use the same.

This invention relates to a hair comb of non-pliable or non-metallic composition or 15 material and including a base or back of standard form, and having flat parallel sides, and teeth integral with and projecting from the inner edge of the base.

The object of the invention is to provide 20 a reenforcing member adapted to strengthen the base of a comb of this description, and to be securely engaged with the flat sides thereof, wholly by friction and without positive attaching means, so that the base 25 may be quickly and securely engaged with the reenforcing member, wholly by the operation of sliding the base into engagement with said member, and without variation of the form of the base from the usual or 30 standard form.

I attain this and other related objects by the improved construction hereinafter described and claimed.

Of the accompanying drawings forming 35 a part of this specification,—

Figure 1 is a side elevation of the reenforcing member.

Figure 2 is an edge view of the same, looking toward the inner edge.

Figure 3 is an enlarged section on line 40 3—3 of Figure 1.

Figure 4 is a side elevation of the comb, with portions in section, and a longitudinal section of the reenforcing member engaged with the comb base.

Figure 5 is a side elevation, showing the comb and the reenforcing member engaged therewith.

The same reference characters indicate the 50 same parts in all of the figures.

The comb includes a base 3, having flat parallel sides, and teeth 4 integral with the base, the comb being of standard form and of any suitable non-pliable and non-metallic 55 composition or material. The reenforcing member shown separately by Figures 1, 2

and 3, comprises a neck 1, bearing on the outer edge of the base, and gripping jaws 1^a integral with and confined by the neck against the major portions of the flat sides 60 of the base.

The reenforcing member may be made of any suitable material, such as celluloid, ebonite or metal. I prefer aluminum, because this metal has suitable strength and 65 lightness.

As shown by Figure 3, the inner surfaces of the jaws 1^a are roughened, to enhance their gripping function and prevent accidental movement of the gripping member 70 on the base.

The comb base is engaged with the reenforcing member by sliding the base endwise into the space or groove 2, between the jaws 1^a, this operation causing the roughened 75 surfaces of the jaws to firmly engage the flat sides of the base, so that although the sides are parallel with each other, as usual in a comb of the standard form, there is no liability of accidental displacement of the reenforcing member on the base. The roughened surfaces may be formed by any suitable means, on a flat blank from which the reenforcing member is formed.

The groove 2 extends continuously from 85 end to end of the reenforcing member, and is open at both ends, so that the comb base may slide endwise into the groove from either end of the reenforcing member. The roughened surfaces of the jaws 1^a are adapted 90 to prevent edgewise withdrawal of the comb base from the groove.

The reenforcing member closely fits all 95 portions of the base inserted in the space or groove 2, so that there are no crevices or spaces liable to receive dirt. The width of the jaws 1^a is such that they do not entirely 100 cover the sides of the comb base, as indicated by Figure 5, major portions of said sides being covered and minor portions exposed between the lower edges of the jaws and the inner ends of the comb teeth, so that there is no liability of entanglement 105 of hair with the edges of the jaws. The ends of the jaws are flush with the ends of the base, as shown by Figure 5.

In case the comb base is broken, as indicated at 5 in Figure 4, the parts of the base may be securely connected by the reenforcing member.

I claim:

The combination with a hair comb which

includes a non-metallic base having flat parallel sides and teeth integral with the base, of a reenforcing member of harder material than the base and formed to closely fit the outer edge and the major portions of the flat sides of the base, said member comprising a neck bearing on the outer edge of the base, and gripping jaws confined by the neck against the major portions of the sides of the base and forming the sides of a groove which is open from end to end, said jaws being provided with roughened internal surfaces engaging the base sides, the

base being slidable endwise into, and entirely filling said groove, and confined therein against edgewise displacement by the engagement of the roughened surfaces with the base sides. 15

In testimony whereof I have signed my name to this specification in the presence of 20 two subscribing witnesses.

JOHN THOMAS FANNING.

Witnesses:

AUGUSTINE THOMAS MADDEN,
IVY DONOHUE.
